PEN BEAM FOR RULING MACHINES

Albert Broadmeyer, Brooklyn, N. Y., assignor to
 John McAdams & Sons, Incorporated, Nor-
 walk, Conn., a corporation of Connecticut

Application September 19, 1939, Serial No. 295,677

4 Claims. (CL 33—34)

This invention relates to pen beams for ruling machines, such beams being, as is well known, the means for supporting ruling pens, and by means of which the pens are raised and lowered to control their operation upon the paper.

The wooden and metal beams heretofore used have been subject to difficulty heretofore unsolved, namely that in struck work the pens have staggered following the striking movement, that is to say, the ends of the pens vibrate from side to side for a brief period after having been brought down on to the paper, resulting in the lines adjacent struck points being wavy, the waves diminishing from the place of striking as the vibrations die out.

One object of this invention is to provide a novel pen beam having all the advantages of previously used beams, and the use of which eliminates staggering or vibration of the pens that it supports.

Another object is the provision in a pen beam of novel pen-clamp that will securely and uniformly grip a number of ruling pens, one that is readily operable, and one in which pens may be easily inserted.

Another object is to provide a pen beam having novel structure that permits ready adjustment of a pen-clamping portion of the beam with relation to the part of the beam that is mounted on the machine.

I have discovered that a beam made of an artificial plastic or resin, aside from having desirable qualities of being non-absorbent and non-warping, has the unexpected characteristic of eliminating staggering of the pens that it carries when ruling struck work.

I attribute this desirable quality of beams made of such materials to a characteristic of the material. Such material has a "dead," or non-resilient characteristic, whereas wood and metal are springy, or resonant. Bodies of wood or metal of the size and shape of pen beams transmit vibrations, and when subjected to impact they set up vibrations. Artificial plastics and resins of similar sizes and shapes do not vibrate when subjected to impacts, and they appear to damp out vibrations instead of transmitting them. Since ruling pens are of thin, springy metal, and project laterally from a pen beam, when such a beam vibrates even slightly, as following the impact of striking, the vibrations are transmitted to the pens and magnified at the points of the pens to cause a very appreciable waving of the ruled lines. Such waves are not found in work ruled upon a machine equipped

with a beam made of the material herein disclosed.

The material that I regard at present as superior for use in pen beams is laminated paper base Bakelite, a commercially available substance that is produced in shapes suitable for manufacturing pen beams. I regard this material as superior as in addition to the above mentioned "dead" characteristic it is extremely strong and is sufficiently resistant to distortion to be satisfactory in use. Any other artificial material having the requisite strength and resistance to distortion, and that has the non-vibratory quality of Bakelite is suitable for substitution.

15 In manufacturing beams of the materials mentioned, it is preferable to make them of a number of strips arranged as laminations. Such a laminated structure may be accurately trued after being assembled, it often being found that 20 the strips as delivered are out of true. A solid, one-piece body of the material is not readily trued when distorted, but a laminated body, in which surfaces of adjacent pieces may slip, may be easily and accurately straightened, and will 25 retain its trued form with completely satisfactory accuracy, whereas a one-piece body will tend to sag when supported at intervals.

The beams illustrated in the accompanying drawings are particularly suitable for employment of the material above mentioned, and when made of such material will eliminate stagger from struck work. It will be appreciated, however, that the beams disclosed have novel structure that is useful when materials heretofore regarded as conventional are employed.

30 In the accompanying drawings:

Figure 1 is a fragmentary perspective view of one form of pen beam embodying this invention;

Figure 2 is a fragmentary bottom plan view;

40 Figure 3 is a fragmentary vertical section;

Figure 4 is a fragmentary perspective of a modified beam having provision for adjusting the lateral position of the pens without disturbing their relative positions;

45 Figure 5 is a fragmentary bottom plan;

Figure 6 is a sectional view on line 6—6 of Figure 5;

Figure 7 is a fragmentary perspective of an other modified beam embodying the invention;

50 Figure 8 is a fragmentary bottom plan; and

Figure 9 is a sectional view on line 9—9 of Figure 3.

Describing the drawings more particularly, and referring first to Figures 1 to 3 and 9, the numeral 10 indicates an elongated body that con-

stitutes the supporting element of a pen beam assembly, and which is arranged for transverse mounting upon a ruling machine in a well known manner.

The rear edge, that is, the edge that is toward the discharge end of the machine when the beam is mounted, and towards the edge of the beam where the pens are supported, is provided with a longitudinally extending groove 11. As mentioned above, it is highly desirable to make beams of Bakelite or other plastic compositions, and this may be conveniently accomplished by forming the body 10 of upper and lower plates 12 of equal width and an intermediate narrower plate 13, the forward edges of the plates being flush 15 so that the groove 11 is provided between rear portions of the plates 12. The plates 12 and 13 are secured together by screws 14, which may be threaded into tapped holes in the material of the plates. A reinforcing angle 15 may be applied to the lower front corner, and a brass covering sheet 16 may be clamped between the forward edges of the plates and the arm of the angle that overlies them.

The pen-clamping portion of the beam comprises a body designated generally 17 that has a forwardly extending tongue 18 that engages in the groove 11 wherein it may be clamped by thumb screws 19, as indicated in Figure 9. Preferably the body 17 is formed of a main plate 20 that extends forwardly to form the tongue 18, and a cap plate 21 that overlies plate 20 and the forward edge of which abuts the rear edge of the upper plate 12.

In order to secure pens, as 22, a plate 23 is secured below the plate 20, such plate 23 having a flat upper surface that underlies in face to face relation the portion of the flat lower surface of the plate 20 that lies rearward of the tongue portion 18. It will be understood that the plates 20, 21 and 23 are preferably made of the Bakelite composition referred to above.

The lower plate 23, which is in effect a clamping jaw that cooperates with plate 20 as the other jaw, is spaced at its forward edge from the under surface of the plate 20 by an interposed spacer 24 which advantageously is in the form of an elongated strip that extends the length of the beam. Tightening members are provided in the form of bolts 25 that extend from the top of the body 17 through the lower plate 23 and that carry wing nuts 26 on their lower ends. It will be seen that when the nuts 26 are tightened and the plate 23 thereby drawn up, the upper surface of the plate will be drawn into angular relation with the lower surface of the main plate 20.

An elastic tongue 27, advantageously of relatively stiff sheet rubber is interposed between the adjacent surfaces of plates 20 and 23. As shown, this tongue may be interposed between the spacer 24 and the under surface of plate 20, and both it and the spacer secured to plate 20 by screws 28, shown in Figure 3. The tongue extends to the rear edges of the plates to provide a resilient and slightly yielding surface against which the pen shanks may be securely clamped. Since it is free from both plates to the rear of the spacer, it also affords a selection in the position in which the pens are mounted, as their shanks may be inserted either above or below the tongue.

In Figures 4 to 6 is illustrated a beam assembly arranged to permit ready lateral motion of the pen-holding portion of the beam upon the 75

supporting portion, a structure that is useful when it is desirable to shift an existing setup of pens in their precise arrangement.

In this embodiment the supporting member is 5 in the form of a metal channel having a bottom web 29 and side arms 30. This channel is arranged for transverse mounting upon a ruling machine.

The pen-holding section of the beam comprises 10 a plate 31, its under surface adjacent the forward edge carrying a pair of oppositely disposed angles 32, arms 33 of which engage and are secured to the under surface of the plate, the depending arms 34 of which are properly spaced to slidably engage opposite surfaces of the walls 30 of the channel, to provide a track for limiting travel of the plate 31 to directions parallel to the walls of the channel. A reinforcing angle 35 is preferably secured to the underside of the 20 plate 31 at its forward edge. The bottom web 29 of the channel is slotted as at 36, shown in Figures 6 and 7, and bolts 37, provided with wing nuts, pass through the plate 31 and slots 36 to provide means for securing the plate 25 against motion.

The rearward portion of the plate 31 corresponds generally with the plate 20 of the previously described embodiment, and supports a 30 similar clamping plate 38, a spacer 39, a tongue 40 and tightening bolts 41, all of which are arranged and operate in precisely the manner of the previously described corresponding elements. Since the flat upper surface of the plate 31 extends the full width of the beam, no cap plate 35 as 21 is necessary. The screws 42 secure the various angles to the underside of the plate 31.

In the embodiment of Figures 7 and 8, the beam and clamp are combined in a single assembly. A main plate 43 extends the full width 40 of the assembly, and to its forward lower surface, by screws 44, is secured a reinforcing member 45. The clamping is accomplished by a jaw plate 46, spaced at its forward edge from the under surface of the plate 43 by a spacer 47, and 45 a tongue 48 being interposed. Bolts 49 provide for the clamping action, this assembly being precisely as described above in connection with the other forms.

In each of the modifications described, it will 50 be apparent that the beams comprise bodies made up of a number of laminations; thus beams so made are peculiarly suitable for manufacture from the artificial materials described above with the attendant advantages mentioned.

Artificial plastics are also peculiarly suited for use in pen clamps of the type common to the various forms of beams illustrated. Such materials are absolutely uniform, and therefore provide a completely uniform clamping as the jaws are both made of such material, which may be accurately finished to precise dimensions throughout the length of the beam. The use of such material not only avoids the non-uniform action of wood, but avoids the difficulty and expense involved in the provision of metal jaws.

From the foregoing it is thought that the construction, operation and many advantages of the herein described invention will be apparent to those skilled in the art without further description, and it will be understood that changes in the size, shape and minor details may be resorted to without departing from the spirit of the invention as set forth in the accompanying claims.

I claim:

1. A pen beam for ruling machines comprising

an elongated supporting member for transverse mounting upon a ruling machine, a pen holding member slidably engaging the upper surface of and supported by the supporting member, means for limiting motion of the pen holding member upon the supporting member to directions that are parallel to the supporting member, and means for securing the pen holding member in adjusted position upon the supporting member.

2. A pen beam for ruling machines comprising a supporting bar in the form of an inverted channel for transverse mounting on a ruling machine, a pen-supporting member overlying and slidable upon said channel and carrying on its lower surface angular means having arms parallel to its under surface and that ride on the edges of the side walls of the channel, said means having also depending arms that slidably engage relatively opposite sides of said channel, means for securing the pen-supporting member in longitudinal adjustment upon the channel, and pen-clamping means carried by the pen-supporting member.

3. Pen clamping means for a ruling machine pen beam, said means comprising a pair of elongated superposed plates adapted for transverse mounting on a ruling machine, said plates having flat surfaces in face to face relation, means

for angularly relating said flat surfaces transversely of the plates, means for bringing the rearward edge of the flat surface of one of the plates into clamping relation with the flat surface of the other plate to form a pen clamp, and an elastic tongue secured to one of the plates forwardly of the said rear edge that forms the clamp, said tongue extending freely from its point of securedment towards and between the edge and surface that form the clamp.

4. Pen clamping means for a ruling machine pen beam, said means comprising elongated superposed members having flat surfaces in face to face relation, said members being adapted for transverse mounting on a ruling machine, the rear edges of the flat surfaces of said members coinciding, an elastic tongue secured between said members forward of their rear coinciding edges and freely extending between said edges, a spacer interposed between the flat surfaces of the respective members at a point forward of their rear edges, and means located between said spacer and said rear edges for drawing together said edges to bring them into clamping relation to form a pen clamp.

ALBERT BROADMEYER.
